UNITED STATES PATENT OFFICE.

GUSTAF A. HERMANSON, OF CHICAGO, ILLINOIS, ASSIGNOR TO
CHARLES H. FERRY, OF CHICAGO, ILLINOIS.

CAR-COUPING.

No. 831,070.

Specification of Letters Patent.

Patented Sept. 18, 1906.

Application filed November 27, 1905. Serial No. 289,150.

To all whom it may concern:

Be it known that I, GUSTAF A. HERMANSON, a citizen of the United States, residing in Chicago, in the county of Cook and State of Illinois, have invented a new and useful Improvement in Car-Couplers, of which the following is a specification.

My invention relates to improvements in car-couplers of the well-known Master Car-Builders' type having a forked draw-head, pivoted knuckle, and gravity locking-pin.

The object of my invention is to provide a car-coupler of a strong, simple, efficient, and durable construction in which the knuckle is automatically thrown open by the lifting of the lock to the required extent.

My invention consists in the means I employ to practically accomplish this object or result—that is to say, it consists in the combination, with the forked draw-head, pivoted knuckle, and vertically-movable gravity locking-pin, of a rotary gear knuckle-thrower journaled to rotate in a suitable chamber in the draw-head, the knuckle and the locking-pin both having racks engaging gear-teeth on the knuckle-thrower.

My invention also consists in the novel construction of parts and devices and in the novel combinations of parts and devices herein shown and described.

In the accompanying drawings, forming a part of this specification, Figure 1 is a central vertical longitudinal section of a car-coupler embodying my invention. Fig. 2 is a horizontal section on line 2 2 of Fig. 1. Fig. 3 is a vertical section on line 3 3 of Fig. 2. Fig. 4 is a detail section of the draw-head on line 4 4 of Fig. 1. Fig. 5 is a detail elevation of the lock. Fig. 6 is a detail section of the knuckle on line 6 6 of Fig. 2, and Fig. 7 is a detail plan view of a portion of the draw-head.

In the drawings, A represents the draw-head of the coupler, the same having the customary guard-arm *a* and pivot-arm *a'* and vertical opening *a*² to receive the lock. B is the knuckle, having the customary front arm *b* and rear arm or tail *b'*, and C is the pivot-pin connecting the knuckle to the draw-head. D is the lock, the same preferably having a movable lifting-piece F, fitting in a longitudinal slot *d* in the lock and having a hook *f*, engaging the cross-pin or shoulder *d'* of the lock. The lifting-piece engages at its lower end a

cam or incline *d*² on the lock when the lifting-piece is in its lowermost position, and thus throws the shoulder *f'* on the lifting-piece under the shoulder *a*³ on the draw-head to prevent the lock from creeping or jumping upward when the cars are coupled together and the train is in motion. The lifting-piece F has a cap or flange *f*³ to close the locking-pin opening in the draw-head and an eye *f*⁴ for connection with the lifting-lever E through the clevis E'. The lock D is also provided with a lock-set ledge or shoulder *d*³, adapted to engage the lock-set leg or shoulder *a*⁴ on the bottom web of the draw-head, and thus set the lock in position for uncoupling. The lock D is also preferably provided with a lock-set ledge or shoulder *d*⁴, adapted to engage and rest upon the rear arm or tail of the knuckle, and thus set or support the lock in position for coupling. All these parts may be of any ordinary or customary construction familiar to those skilled in the art.

The draw-head is further provided in its upper portion at one side of the lock with a recess or chamber *a*⁵ to receive a rotary-gear knuckle-thrower G and with slot or bearing-guide *a*⁶ to receive and confine the shaft portion *g* of the knuckle-thrower. The rotary knuckle-thrower G has a gear *g*' meshing with a rack *b*² on the upper face of the knuckle B and operating to throw the knuckle open when the rotary knuckle-thrower is turned on its axis. The rotary knuckle-thrower G also has gear-teeth *g*², which mesh with a rack *d*⁵ on the locking-pin D when the lock is lifted to the required extent, thus rotating the knuckle-thrower and throwing the knuckle open. The rotary knuckle-thrower G also has a circular boss *g*³, which rests upon the upper face of the knuckle, and thus supports the knuckle-thrower on the knuckle. The shoulders *a*⁷ at the ends of the guide-slot *a*⁶ prevent the knuckle-thrower from moving longitudinally in the draw-head. The rear arm or tail of the knuckle has a hook or projection *b*³, which when the knuckle is closed fits in the slot or recess *a*⁸ of the draw-head and tends to relieve the pivot-pin from strain. The bottom web or floor of the draw-head is also provided with a ledge or shoulder *a*⁹, which engages the flange or shoulder *b*⁴ on the rear arm or tail of the knuckle and affords a further connecting means between the knuckle and draw-head.

- when the knuckle is closed and tends to relieve the pivot-pin from strain. The upper web of the draw-head is also preferably furnished with a ledge or shoulder a^10 , which engages a flange or shoulder b^5 on the upper face of the knuckle and serves as a still further means for connecting the knuckle with the draw-head when the knuckle is closed and of relieving the pivot-pin from strain.
10. I claim—
1. In a car-coupler, the combination with a draw-head, of a knuckle having a rack, a lock having a rack, and a rotary-gear knuckle-thrower interposed between the lock and knuckle, substantially as specified.
  2. In a car-coupler, the combination with a draw-head, of a knuckle having a rack, a lock having a rack, a rotary-gear knuckle-thrower interposed between the lock and knuckle, the draw-head having a recess or chamber to receive the knuckle-thrower, and the knuckle-thrower having two gears, one meshing with the rack on the knuckle-thrower and the other meshing with the rack on the lock, substantially as specified.
  3. In a car-coupler, the combination with a draw-head, of a knuckle having a rack, a lock having a rack, a rotary-gear knuckle-thrower interposed between the lock and knuckle, the draw-head having a recess or chamber to receive the knuckle-thrower, and the knuckle-thrower having two gears, one meshing with the rack on the knuckle-thrower and the other meshing with the rack on the lock, the draw-head being also provided with a guide-slot to afford a bearing for the shaft portion of the knuckle-thrower, substantially as specified.
  4. In a car-coupler, the combination with a draw-head, of a knuckle having a rack, a lock having a rack, a rotary-gear knuckle-thrower interposed between the lock and knuckle, the draw-head having a recess or chamber to receive the knuckle-thrower, the knuckle-thrower having two gears, one meshing with the rack on the knuckle-thrower and the other meshing with the rack on the lock, the draw-head being also provided with a guide-slot to afford a bearing for the shaft portion of the knuckle-thrower, and the knuckle-thrower having a shaft portion at each end thereof and also between the two gears thereon, substantially as specified.
  5. In a car-coupler the combination with the draw-head, of a knuckle provided with a rack, a lock provided with a rack and a rotary-gear-toothed knuckle-thrower having a circular boss portion resting on the tail of the knuckle, substantially as specified.
  6. In a car-coupler, the combination with a draw-head, of a knuckle having a rack, a lock having a rack, and a rotary-gear knuckle-

thrower interposed between the lock and knuckle, the lock having a lock-set ledge or shoulder and provided with a movable lift-
ing-piece furnished with a shoulder to prevent creeping of the lock, substantially as specified.

7. In a car-coupler, the combination with the draw-head, of a knuckle having a rack on its upper face, a vertically-movable locking-pin, a rotary knuckle-thrower having a gear meshing with the rack on the knuckle and means for rotating the knuckle-thrower by the lifting of the locking-pin, substantially as specified.

8. In a car-coupler, the combination with the draw-head, of a knuckle having a rack on its upper face, a vertically-movable locking-pin, a rotary knuckle-thrower having a gear meshing with the rack on the knuckle and means for rotating the knuckle-thrower by the lifting of the locking-pin, the lock having a lock-set ledge or shoulder to engage the draw-head, substantially as specified.

9. In a car-coupler, the combination with the draw-head, of a knuckle having a rack on its upper face, a vertically-movable locking-pin, a rotary knuckle-thrower having a gear meshing with the rack on the knuckle, means for rotating the knuckle-thrower by the lifting of the locking-pin, and a movable lifting-piece on the lock having a shoulder engaging a shoulder on the draw-head to prevent creeping of the lock, substantially as specified.

10. In a car-coupler, the combination with a forked draw-head, of a knuckle having a rear arm or tail furnished with a rack, of a locking-pin furnished with a rack, and a rotary knuckle-thrower having a gear meshing with the rack on the knuckle and another gear meshing with the rack on the locking-pin, substantially as specified.

11. In a car-coupler, the combination with a draw-head furnished with a chamber and bearing for a rotary-gear knuckle-thrower, of a knuckle having a rack engaging the rotary gear knuckle-thrower and a lock having a rack also engaging the rotary-gear knuckle-thrower, substantially as specified.

12. In a car-coupler, the combination with a draw-head having a chamber to receive a rotary knuckle-thrower furnished with gear-teeth, of a knuckle having a rack on its upper face engaging the teeth of the knuckle-thrower, and a vertically-movable locking-pin and means for causing the lock to rotate the knuckle-thrower when the lock is lifted to the required extent, substantially as specified.

GUSTAF HERMANSON.
